UNITED STATES PATENT OFFICE.

WILLIAM J. BROOKMAN, OF CHICAGO, ILLINOIS.

HAND-STAMP.

1,196,512.

Specification of Letters Patent. Patented Aug. 29, 1916

Application filed March 20, 1916. Serial No. 85,359.

To all whom it may concern:

Be it known that I, WILLIAM J. BROOKMAN, a citizen of the United States, and resident of Chicago, county of Cook, and 5 State of Illinois, have invented certain new and useful Improvements in Hand-Stamps, of which the following is a specification, and which are illustrated in the accompanying drawings, forming a part thereof.

10 The invention relates to stamps, such as are used upon the desk for printing the date, a signature or the like, and the invention has especial reference to the manipulation of these stamps by hand. As usually 15 constructed the type with which these stamps are provided is either normally concealed from view or is so located with reference to the handle as not to be visible during the ordinary use of the stamp. 20 Furthermore, as these stamps are commonly formed with a body which is of symmetrical shape, the use of the stamp required either an examination of the type or of some visible marker upon the body of the stamp in 25 advance of the printing operation, to prevent printing with the type in an inverted position.

The present invention accordingly proposes to avoid the necessity of a visual examination of the stamp, by providing the 30 stamp body with a handle which serves to indicate the position of the type when grasped by the hand in ordinary use of the stamp.

35 The object of the invention is to provide a hand stamp which may be more conveniently and rapidly used.

In the accompanying drawings, Figure 1 is a perspective view showing a well known 40 form of self inking hand stamp embodying the features of improvement provided by the invention, Fig. 2 is a plan view of the stamp illustrated in Fig. 1, Fig. 3 is a plan view showing a different form of stamp embodying the features of improvement provided by the invention, and Fig. 4 is an end elevation of the stamp illustrated in Fig. 3.

In carrying out the invention the stamp frame or body, as 10 or 11, will be constructed as usual and an improved form of handle, as 12 or 13 is applied thereto. This handle is so shaped that it not only serves

to indicate the position of the corresponding stamp frame or body 10 or 11 when grasped in the hand, but the shape is such as to facilitate the holding of the stamp when turned to the correct position for printing. To this end the handle 12 or 13 is provided with a forwardly projecting knob, as 14 or 15, to be received between the fingers of the hand.

When the stamp frame or body, as 10, is of such shape that the handle 12 is raised a considerable distance above the printing plane, the forwardly projecting knob 14 is 65 most conveniently located at the lower end of the handle, as in Figs. 1 and 2. On the other hand, when the frame or body, as 11, merely comprises the usual wooden block to which the type, as 16, is directly applied, 70 and the handle, as 13, is accordingly separated only a short distance from the printing plane, the forwardly projecting knob, as 15, is preferably located near the upper end of the handle.

With either form of construction shown, the forwardly projecting knob, 14 or 15, is laterally compressed to be conveniently received between the fingers of the hand and is of rounded outline. As a handle provided with this forwardly extended knob will be most conveniently grasped in the hand when the knob is directed toward the user, the improved handle not only serves as an indicator to denote the position of the stamp, but it greatly reduces the liability of using the stamp with the type in inverted position even through no conscious attention is given to the position of the projection by the user. The convenience and rapidity with which the stamp may be used are thereby greatly increased.

I claim as my invention,—

In a device of the kind described, in combination, a stamp body having a type face, 95 a non-symmetrical upright handle secured to the stamp body and having a laterally compressed knob to be gripped between the fingers formed on an upright side of the handle and projecting forwardly 100 therefrom with respect to the printing line of the type face of the body when in printing position.

WILLIAM J. BROOKMAN.
